UNITED STATES PATENT OFFICE.

JOHN W. HALL, OF SAYRE, PENNSYLVANIA.

DESIGN FOR A BRIDGE FOR GAMES.

SPECIFICATION forming part of Design No. 34,639, dated June 11, 1901.

Application filed April 4, 1901. Serial No. 54,400. Term of patent 14 years.

To all whom it may concern:

Be it known that I, JOHN W. HALL, a citizen of the United States, residing at Sayre, in the county of Bradford and State of Pennsylvania, have invented and produced a new and original Design for a Bridge for Games, of which the following is a specification:

The present invention relates to a novel design of a bridge for games; and the object thereof is to provide a new, useful, and original design of this character.

The leading feature of this design resides in a platform comprising two correspondingly-shaped plates or sections which taper, respectively, toward one end, said plates or sections being joined together at their tapered ends and located at an angle to each other, whereby the platform will incline downwardly from its central portion.

A further feature resides in providing continuous upstanding side flanges upon the opposite side edges of the platform, said flanges terminating short of the ends of the platform, whereby an open-ended guideway or passage-way is formed which is contracted at its central portion.

The minor features reside in a transversely-disposed supporting-rib located upon the under side of the platform at the point of juncture of the inclined sections and in beveling off the terminal edges of the projecting portions of said sections.

In the drawings, Figure 1 is a perspective view of a bridge for games embodying the present design. Fig. 2 is a top plan view of the same.

Similar numerals of reference designate cor-

responding parts in both figures of the drawings.

The platform is designated as a whole in 40 the drawings by the reference-numeral 10, and comprises the two correspondingly-shaped plates or sections 10^a, which respectively taper toward one end, said plates or sections being joined together at their tapered ends and 45 located at an angle to each other, whereby the platform 10 will incline downwardly from its central portion, which central portion will be narrower than the ends.

Continuous upstanding side flanges 11 are 50 located upon the opposite side edges of the platform; said flanges terminating short of the ends of the platform, whereby an open-ended guideway or passage-way 12 is formed; which passage-way is contracted at its central 55 portion.

A supporting-rib 13 is located transversely upon the under side of the platform at the point of juncture of the inclined sections 10^a, and the terminal edges of the projecting end 60 portions 14 of the platform 10 are beveled.

Having now described the invention, what I claim as new, and desire to secure by Letters Patent, is—

The design of a bridge for games as herein 65 shown and described.

In testimony that I claim the foregoing as my own I have hereto affixed my signature in the presence of two witnesses.

JOHN W. HALL.
